GEORGE J. OLTSCHE, OF SOUTH BEND, INDIANA.

BOX-END-STAPLING MACHINE.

1,050,844.

Specification of Letters Patent. Patented Jan. 21, 1913.

Application filed May 29, 1911. Serial No. 630,913.

To all whom it may concern:

Be it known that I, GEORGE J. OLTSCHE, a citizen of the United States, residing at South Bend, in the county of St. Joseph and 5 State of Indiana, have invented certain new and useful Improvements in Box-End-Stapling Machines, of which the following is a specification.

This invention relates to improvements in 10 stapling machines, and more especially to those types of machines particularly adapted for stapling box ends in the manufacture of wire-bound boxes.

In the manufacture of such boxes it has 15 been found desirable to drive the staples from the inner sides of the ends, the ends being of thinner lumber than the cleats, and secure the ends against the inner sides of the end cleats of the blank by driving the 20 staples through the ends into the cleats. In driving the staples from the inner sides of the box, it has been found in practice to be very advantageous in assembling and holding 25 the box parts, and moving the same during the stapling operation by hand, that the staples be driven in an upward direction.

The object of my invention is to provide 30 a stapling machine in which the staples are delivered to the driving means in an inverted position, without the use of any movable delivering mechanism, thus greatly simplifying the structure and entirely abolishing the comparatively complex actuated mechanisms now employed in the art for that purpose.

In carrying out my invention I prefer to 40 provide the machine with staple forming means, although it is to be understood that the machine may be arranged to use ready formed staples without departing from the spirit of my invention, which relates primarily to the new and novel means employed for delivering the staples inverted to the driving means, and in connection with 45 which any suitable staple forming or supplying means may be employed.

Referring to the drawings, in which are 50 shown the preferred embodiment of my invention—Figure 1 is a side elevation, partly in section, of the head end of a stapling machine illustrating the invention. Fig. 2 is a horizontal sectional view taken on the line $\alpha-\alpha$ of Fig. 1.

The machine head comprises the frame 1, 55 which is the extreme end of a horizontal arm

supported in the usual manner by a standard (not shown), and upon which standard the requisite pulleys and cams are mounted for actuating, through the medium of suitable connections, the staple forming, staple driving and wire feeding mechanisms, all of which are arranged to operate in their proper order. As such actuating means are old in the art and forming no material part of the present invention, an illustration and description thereof is dispensed with, it being sufficient for a clear understanding of the present invention to know that any suitable devices may be employed for actuating the staple forming, staple driving and wire feed devices which are illustrated in the drawings and described herein. A plate 2, mounted in guides 3 and 4, to be reciprocated up and down, carries a staple driver 5. The plate 2 is reciprocated by a rocking lever 6, which is pivotally connected with the plate by a pin 7, which projects through a slot 8 in the vertical wall of the frame, the rocking lever and head being disposed on opposite sides of said wall. Secured to the frame, as by means of screws, is an irregular shaped plate 9, having an extended arm 10 provided with a central vertical slot 11, and an opening 12 intersecting said slot and passing entirely through the arm, said opening being somewhat larger than the slot, and into which the staple forming plunger, hereinafter described, is projected. The slot 11 is open at its upper end and the lower wall thereof is on a slant to form an incline, down which the formed staple deposited in the slot slides into the vertical staple guide 13, in which the staple driver 5 is arranged to slide. An opening 14 is arranged in the plate 9 in alinement with the opening 12, and slotted in its upper and lower sides, as indicated at 15 and 16, to form a die, through which the wire is forced by the staple forming plunger and bent into the regulation U-shaped form of a staple. A plate 18 secured to the frame, as by screws, and in spaced relation with the plate 9, is provided with openings 19 and 20, in alinement respectively with the openings 14 and 17 in the plate 9, and through which openings the staple forming plunger, and a cutter member for severing the wire into proper lengths, reciprocate.

Fixedly secured between the opposite edges of the plates 9 and 18, is a pin 21,

the upper end of which is tapered and provided with a central longitudinal bore. A curved tubular guide 22, fixedly secured to the frame, adjoins said pin at its lower end, the lower end of the guide being disposed in line with a wire feed device, presently explained, so that the wire will be fed through the guide and pin from a horizontal to a vertical position, and in line to be operated upon by the staple forming plunger and wire cutting device. The wire feeding device consists of a pair of serrated jaws 23, 23, tapered at their outer edges, and disposed between the converging walls 15 of a reciprocated block 25, the serrated edges of the jaws being held in gripping relation with the wire, on the feed stroke of the block, by a spring 26, which forces the jaws toward the converging walls of the block. On the return stroke of the block, the jaws move toward the diverging ends of the walls against the tension of the spring, and release their grip upon the wire, at which time the wire is held against retractive movement by a sharp edged finger 27, which contacts with the exposed wire through a cut-out portion in the guide, as shown, whereby any downward movement of the wire causes the finger to bind the wire against the wall of the guide, while permitting a free upward movement of the wire without a binding action thereon. The block 25 is actuated by a cam (not shown) so as to intermittently feed a length of wire, and at the proper time, to be formed into a staple in a manner presently explained.

Immediately after the proper length of wire has been fed in line to be acted upon by the staple forming plunger and wire cutting device, those members are actuated to perform their several functions. The staple forming plunger 28 is carried by a reciprocating head 29, which slides in guides 30 and 31 secured to the frame, and which head also carries a pivoted finger 32, normally pressed inwardly by a spring 33. The free end of the finger is shouldered at 34, and engages the head 35 of a wire cutting member 36, having a cutting edge 37 on an angle corresponding with the upper tapered end of the pin 21. The finger 32 is provided with a laterally projecting trip finger 38, which engages a cam block 39 when the finger has been moved forward a sufficient distance for its end to sever the wire, and disengages the end of the finger from the head end of the cutting member, whereupon the latter, under the influence of the spring 40, is returned to its normal position, while the finger 32 continues its stroke with the head with which it is pivotally connected, its end sliding upon the plate 18, to one side of the cutter member. A stop pin 41 limits the movement of the cutter member in one direction, and against which said

member normally rests, the end of the finger 32 being forced against the frame after it passes the head end of the cutting member, and in line with the latter, so that upon the next forward stroke, the end of the finger will abut with the head end of the cutting member, and the operation above described repeated. Simultaneous with the severing of the wire, the end of the plunger 28 engages the severed part intermediate its ends and forcing the same through the slotted opening 14, bends the wire into the U-shaped form of a staple. The stroke of the plunger continues until the points of the staple have passed a stripping finger 42, pivotally connected to the frame, the free end of which is raised by the staple contacting with the rounded under side of the laterally projecting portion thereof, and drops by gravity as soon as the staple has passed the same, so that upon the return stroke of the plunger the staple ends will contact therewith and the staple will be stripped from the plunger.

As the staple is stripped from the plunger, it falls and slides down the inclined slot 11, its head end contacting with one pole of a magnet, the poles 44 and 45 of which are exposed on one side through the wall of the vertical staple guide 13, while the magnetic attraction of the opposite pole upon the upper leg of the staple will cause the same to tilt and be held by magnetic attraction, with the points thereof directly upwardly, and properly disposed within the guide 13 to be acted upon by the driving member. Even though the magnet used should not be strong enough to attract the staple to a vertical position, the slightest upward movement of the staple driver will, owing to the resistance of the magnet against moving the staple, which is in contact therewith at one side thereof, cause the same to swing into a vertical position, and in consequence of which a permanent magnet may be advantageously used. The magnet illustrated in the drawings is of the horseshoe type, with its ends bent so as to fit around the nose of the machine frame, and its major portion seated in a cavity in the side of the frame, as represented by dotted lines in Fig. 2. It is obvious that an electromagnet or any other suitable type of magnet may be used for the purpose herein described.

Having thus described my invention, what is claimed is—

1. In a stapling machine, the combination with mechanism for driving a staple in an upward direction, of means for delivering the staple by gravity to the driving mechanism in a position out of the vertical, and magnetic means for attracting the staple to a vertical position and holding the same to be acted upon by the driving mechanism.

2. In a stapling machine, the combination with staple forming and upwardly driving mechanism, of inclined means for guiding and delivering the staple from the forming to the driving mechanism by gravity, and magnetic means for attracting the staple from an inclined to a vertical position with the points uppermost, and holding the same in the path of the driving mechanism.
- 10 3. In a stapling machine, the combination with means for delivering the staple head-end foremost, of means for driving the staple upwardly, a vertical guide for the staple and the driving means, an inclined guide for receiving and delivering the staple to the vertical guide by gravity, and a magnet disposed opposite the lower end of the inclined guide, whereby the head-end of the staple will strike the magnet at an angle
- 15 20 and the points thereof will be attracted upwardly and held in driving position.
4. In a staple forming and driving machine, the combination with a staple former adapted to deliver the staple in a horizontal position, of means for driving the staple upwardly, a vertical guide for the staple and the driving means, an inclined guide for receiving and conducting the staple by gravity to the driving mechanism, and a magnet disposed opposite the lower end of the inclined guide, whereby the head-end of the staple will contact with the magnet and the points thereof be attracted to and held in a
- vertical position to be acted upon by the driving means.
5. In a stapling machine, the combination with staple forming and driving mechanism, of a guide member provided with an inclined slot to receive and deliver the staple by gravity, a vertical guide for the staple and for the driving mechanism, and a magnet exposed through the wall of the latter guide to attract and hold the staple in a vertical position within said guide.
6. In a stapling machine, the combination with mechanism for driving a staple in an upwardly direction, of means for delivering the head-end of a staple to a point above the driving mechanism and in a position out of the vertical, and magnetic means for attracting the driving points of the staple upwardly into position for upwardly driving.
7. In a stapling machine, the combination with a staple driver, of a fixed guide for the driver and staple, means for partially delivering a staple to the guide head-end foremost, and means within the guide for shifting the points of the staple upwardly into position for upwardly driving.
- In testimony whereof I affix my signature in presence of two witnesses.

GEORGE J. OLTSCH.
